CLAIM

The ornamental design for a rain fade shield for satellite dish, as shown and described.

DESCRIPTION

FIG. 1 is a top plan view of the rain fade shield for satellite dish showing my new design, the bottom plan view being a mirror image thereof;

FIG. 2 is a front view thereof;

FIG. 3 is a side view thereof, the other side being a mirror image thereof;

FIG. 4 is a back view thereof; and,

FIG. 5 is a perspective view thereof, on a reduced scale, in a modified position and shown in use.

The satellite dish shown in broken lines in FIG. 5 denotes the nature and environmental use of the design and is not part of the claimed design.
